COMBINATION BOUDOIR CHAIR AND DETACHABLE BACK REST

Herman Lee Harris, Elkins Park, Pa.

Application January 15, 1953, Serial No. 23,151

Term of patent 3½ years

(Cl. D15—1)

To all whom it may concern:

Be it known that I, Herman Lee Harris, a citizen of the United States, residing at Elkins Park, in the county of Montgomery and State of Pennsylvania, have invented a new, original, and ornamental Design for Combination Boudoir Chair and Detachable Back Rest, of which the following is a specification, reference being had to the accompanying drawing, forming part thereof.

In the drawing:

Fig. 1 is a perspective view of a combination boudoir chair and detachable back rest, showing my new design.

Fig. 2 is an exploded view in perspective showing the detachable back rest separated from the chair.

I claim:

The ornamental design for a combination boudoir chair and detachable back rest, as shown.
